UNITED STATES PATENT OFFICE.

HENRY P. DE ZETTER, OF BYRON, NEW YORK.

SEPARATOR.

1,048,052.

Specification of Letters Patent. Patented Dec. 24, 1912.

Application filed May 11, 1912. Serial No. 696,646.

To all whom it may concern:

Be it known that I, HENRY P. DE ZETTER, a citizen of the United States, residing at Byron, in the county of Genesee and State 5 of New York, have invented certain new and useful Improvements in Separators, of which the following is a specification.

The object of this invention is to provide a machine for separating various kinds of 10 grains but more especially for separating and grading beans. That is, separating the round, heavy, well formed beans from the light or poorly developed or mis-shaped beans and from the small stones, dirt, etc., 15 with which they may be associated or mixed. The beans referred to are the white beans such as are used for soup or baking which when in normal condition are well filled out and rounded.

20 Another object of my invention is to increase the separating capacity of the machine so that the beans will pass through the machine more quickly than ordinarily.

Another object of my invention is to provide 25 a machine with an improved form of feed regulating device by which the feed of the beans to the separating mechanism is controlled.

These and other objects of my invention 30 will be fully illustrated in the drawings, described in the specification and pointed out in the claims at the end thereof.

In the accompanying drawings, Figure 1 illustrates a front elevation of my improved 35 separating machine as viewed from the right in Fig. 3. Fig. 2 is a side elevation of the duplex machine constructed according to my invention. Fig. 3 is a sectional elevation of my machine which section is taken on the line 3^x—3^x in Fig. 1. Fig. 4 is an enlarged 40 detail sectional view of the feed regulating mechanism, section being taken on the line 4^x—4^x of Fig. 1. Fig. 5 is a longitudinal section through the machine shown in Fig. 2.

45 In the accompanying drawings, like reference characters refer to like parts.

My improved separating machine consists of a framework 1 having the rollers 2, 3 mounted therein at the upper and lower ends

thereof respectively. This framework is 50 pivotally mounted at 5 on the legs 4 at the lower end and is also pivotally mounted on the adjustable support 6 at the upper end. This adjustable support has the threaded stem 7 thereon which passes through the 55 bracket 8 and is supported thereon by the nut 9. By the turning of the nut 9, the framework 1 can be swung around the pivot 5 and any angular adjustment of the framework can be secured.

60 Mounted in the framework 1 is the separating table 10 and between the rollers 2 and 3 passes the endless belt or apron 11, the movement of which is indicated by the arrows shown in Fig. 3. This table controls 65 the middle section which is sufficiently parallel to the long sides of the framework 1, above which is the upper section which slants toward the horizontal and below which is the lower section which slants toward the vertical and the pitch of the slope being decreased in the upper section and being increased in the lower section differing in this respect from the pitch of the middle section.

75 Mounted on the framework 1 is the hopper 12 having the feed openings 13 in the bottom thereof, each of which feed openings is controlled by the feed regulator 14 which feed regulators are mounted on and rotate 80 with the shaft 15, such as is shown in Fig. 1. Each of these feed regulators is composed of a pair of disks 16 between which is placed a wheel having pockets or recesses 17 therein. Fastened to the bottom of the hopper 12 85 are the guards 18 which bear against the wheel of the feed regulator and prevent the beans or grain from working down back of the feed regulator and compel all of the material to be separated to pass over the feed 90 regulator onto the separating apron 11.

As shown in Figs. 3 and 4, the material to be separated is placed in the hopper 12 and is conveyed therefrom by the feed regulator 14 onto the apron 11. The material is discharged upon the apron immediately over the intermediate section of the table 10. The frame 1 is pitched at such an angle so

that the sound heavy beans will roll down the intermediate portion of the table faster than the belt 11 is traveling upwardly thereon, so that such beans will rapidly approach 5 the steeply inclined portion of the table at the end thereof. When the sound beans reach the lower portion of the table, they will roll faster due to the increased steepness of the incline and pass off from the end 10 thereof into the chute 20. The light or misshaped beans will not roll down as fast as the belt travels up and will be carried above the middle portion of the table 10 onto the upper end thereof which is less steeply in- 15 clined, after which they will cease to roll at all and will be carried up over it practically as fast as the belt travels. They will pass over the roller 2 and will be discharged into the chute 21 onto the table. By raising or 20 lowering the upper end of the frame 1, the proper incline of the table 10 can be secured by which the separating machine will work with the most efficiency and despatch.

In Figs. 2 and 5, I have shown views of 25 the duplex machine. In this machine all of the beans are dumped into a single hopper 25 at the top, from which they are fed into the hoppers 26 and 27 and pass therefrom through the feed regulators 28 and 29 onto 30 the belts 30 and 31 which traverse the separating tables 32 and 33. The heavy beans are discharged into the spout 34 along which they are lined by the conveyer worm 35, while the light beans are discharged into 35 the chutes 36 and 37 at the opposite ends of the machine. The machine shown in Figs. 2 and 5 is mounted on the base 38 on which are mounted the uprights 39, 40, 41 and 42, from which the various parts of the machine 40 are supported. On these uprights are supported the upright frames 43 on which are mounted to run, a pair of cone pulleys 44 and 45. The pulley 44 is a driving pulley and the pulley 45 is a driven pulley. Car- 45 ried on the pulley 45 on the shaft thereof, are the pulleys for which belts run for driving the various parts of the machine. The belt 46 is used for driving the worm, the belt 47 for driving the nearest feed regulating 50 shaft from which in turn the farthest feed regulating shaft is driven by the cross-belt 48. The belt 49 is also used for driving the nearest upper roller 2 and the cross belt 50 is used to convey the power therefrom to the 55 opposite roller 2. By shifting the belt 51 laterally on the cone pulleys 44 and 45, any desired variation in the speed for operating the machine may be secured.

In the operation of my machine, the beans 60 are dumped into the hopper and pass through the feed regulator 14 which deposits them in small streams upon the upwardly moving belt. The heavy beans at once begin to roll down the belt faster than

the belt travels up while the light beans roll 65 down more slowly than the belt travels up or do not roll down at all. Thus the heavy beans soon reach the steep, inclined portion of the table at the bottom thereof, while the light beans soon reach the upper portion of 70 the table which is almost horizontal. The separation is thus quickly effected and the high-grade beans are deposited into the lower chute while the low grade beans are carried into the upper chute. 75

Having thus described my invention, what I claim as new and patentable is as follows:

1. In a separating machine, the combination of an inclined table, a belt traveling up 80 over the said inclined table, said inclined table having three grades of inclination thereon arranged progressively from top to bottom, the lightest inclination being at the top and the heaviest inclination at the 85 bottom.

2. In a separating machine, the combination of a frame, a table secured therein, a belt mounted to travel over said table, said table having three grades of inclination 90 thereon, the middle part of said table having a moderate inclination, the upper part of said table having a light inclination and the lower part of said table having a heavy inclination. 95

3. In a separating machine, the combination of a frame, a table secured therein, a belt mounted to travel over said table, said table having three grades of inclination therein, the middle part of said table having 100 a moderate inclination, the upper part of said table having a light inclination and the lower part of said table having a heavy inclination, rollers at each end of said table, said belt traveling over said rollers and said 105 table, a chute adjacent to each of said rollers.

4. In a separating machine, the combination of an inclined table, an endless im- 110 pervious belt traveling up over said inclined table, said table having a plurality of grades of inclination thereon arranged progressively from top to bottom, the lightest inclination being at the top and the heaviest inclination at the bottom, said belt moving 115 continuously in one direction and being adapted to receive unsorted grain thereon and to separate it by the movement of the belt and inclination of the table and discharge the sorted material at the opposite 120 ends thereof.

5. In a separating machine, the combination of an inclined table, an endless im- 125 pervious belt traveling up over said inclined table, said table having two grades of inclination thereon arranged progressively from top to bottom, the lightest inclination being at the top and the heaviest

inclination at the bottom, said belt moving continuously in one direction and being adapted to receive unsorted grain thereon and to separate it into grades by the movement of the belt and inclination of the table, and discharge the different grades at the opposite ends thereof.

In testimony whereof I affix my signature in presence of two witnesses.

HENRY P. DE ZETTER.
